CLAIM

The ornamental design for a computer plug housing, as shown and described.

DESCRIPTION

FIG. 1 is a perspective view of the computer plug housing of the invention;

FIG. 2 is a front elevational view of the computer plug housing of FIG. 1 housing;

FIG. 3 is a top view of the computer plug housing of FIG. 1; FIG. 4 is a rear elevational view of the computer plug housing of FIG. 1;

FIGS. 5 and 6 are side elevational views of the computer plug housing of FIG. 1;

FIG. 7 is a bottom view of the computer plug housing of FIG. 1; and,

FIG. 8 is a rear elevational view of another embodiment of the computer plug housing of the invention.

All other views of the second embodiment are the same as the first embodiment.
